US00D944310S

(12) **United States Design Patent** (10) **Patent No.:** **US D944,310 S**
(45) **Date of Patent:** **** Feb. 22, 2022**

(54) **PROJECTOR SYSTEM**

(71) Applicant: **GDC TECHNOLOGY (SHENZHEN) LIMITED**, Shenzhen (CN)

(72) Inventor: **Man Nang Chong**, North Point (HK)

(73) Assignee: **GDC TECHNOLOGY (SHENZHEN) LIMITED**, Shenzhen (CN)

(**) Term: **15 Years**

(21) Appl. No.: **29/735,097**

(22) Filed: **May 18, 2020**

(30) **Foreign Application Priority Data**

Mar. 5, 2020 (CN) 202030071290.5

(51) LOC (13) Cl. **16-02**

(52) U.S. Cl.

USPC **D16/230**; D16/225

(58) **Field of Classification Search**

USPC D16/221, 225, 230-231, 234; D21/514
CPC G03B 21/145; G03B 21/14; G03B 21/16;
G03B 21/001; G03B 21/003; G03B
21/12; G03B 21/00

(57) **CLAIM**

The ornamental design for a projector system, as shown and described.

DESCRIPTION

FIG. 1 is a front view of the projector system;
FIG. 2 is a back view of the projector system;
FIG. 3 is a left side view of the projector system;
FIG. 4 is a right side view of the projector system;
FIG. 5 is front right perspective view of the projector system;
FIG. 6 is a front left perspective view of the projector system;
FIG. 7 is a front top perspective view of the projector system; and,
FIG. 8 is a front left bottom perspective view of the projector system.

The broken lines shown in the drawings are included for the purpose of illustrating portions of the projector system and form no part of the claimed design.
